UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

ROLLER SKATE.

Application filed January 20, 1922. Serial No. 530,675.

To all whom it may concern:

Be it known that I, ARTHUR L. STAPLES, citizen of the United States, residing at New Haven, in the county of New Haven 5 and State of Connecticut, have invented new and useful Improvements in Roller Skates, of which the following is a specification.

The present invention relates to roller skates and more particularly to skates of 10 the type having a longitudinally extensible foot plate which is reinforced to prevent bending or buckling of the same.

One object of the invention is to provide a skate of the general type above indicated 15 having improved and reliable reinforcing means for imparting the requisite rigidity to the foot plate.

Another object of the invention is to provide, in a roller skate having a heel plate 20 and a toe plate arranged for relative longitudinal adjustment, improved means for preventing relative flatwise and lateral edge-wise displacement of said plates.

A still further object of the invention is 25 to produce an extensible roller skate of a simple, durable and commercially practical construction having its parts compactly arranged and so designed that the skate will present an unusually neat and pleasing appearance.

With these objects in view, the invention 30 consists in the features of construction and in the combinations and arrangements of parts hereinafter described and claimed.

The invention will be best understood 35 from a description of the preferred embodiment thereof illustrated by the accompanying drawings, in which:—

Fig. 1 is a plan view of the improved 40 skate; and

Figs. 2 and 3 are sectional views thereof, the sections being taken on the lines 2—2 and 3—3, respectively, of Fig. 1.

The skate shown in the drawings is provided 45 with an extensible footplate comprising two sections, namely, a heel plate 5 and a toe plate 6, which are capable of longitudinal sliding adjustment relatively to each other. The heel plate 5 is formed with a forward extension 7 while the toe plate 6 is provided with a rearward extension 8 and said plates are assembled with their extensions in overlapping relation and rigidly but adjustably secured together by means 50 of a fastening device 9. Preferably, as

shown, the heel plate extension 7 overlies the toe plate extension 8 and the fastening device 9 comprises a bolt 10 extending through the heel and toe plate extensions, a nut 11 threaded upon the bolt, and a clamping shoe 12 loosely surrounding the bolt between the nut and the toe plate extension. The nut 11 serves to bind the extensions together between the head of the bolt and the clamping shoe 12. A split spring washer 14 is interposed between the nut 11 and the clamping shoe 12 and tends to prevent the nut from working loose after it has been tightened. To permit the described sliding adjustment of the heel and toe plates, 60 the extension 8 of the latter is provided with an elongated longitudinal slot 15 through which the bolt 10 extends. By thus forming the slot 15 in the toe plate extension which underlies the heel plate extension, the slot will be entirely covered by the heel plate extension when the foot plate is contracted, thus giving the effect of a 70 solid foot plate when viewed from above. Normally the fastening device 9 serves to 75 securely hold the toe and heel plates against longitudinal displacement. By loosening the nut 11 of the fastening device, the toe and heel plate may be readily shifted longitudinally with respect to each other to adjust the skate to shoes of different sizes. 80

As shown in Fig. 2, the toe plate extension 8 is depressed below the plane of the main portion of the toe plate to enable the latter to lie in substantially the 85 same plane as the heel plate and the outer end of the slot 15 is closed to limit the extension of the foot plate. For releasably attaching the skate to a shoe, the heel plate 5 is provided with the usual heel band 16 and ankle strap 17 while the toe plate is 90 provided with toe clamps 18 which are adjustable into engagement with the edge of the shoe sole by means of an adjusting screw 20 as is customary in skate construction. 95

Depending from the toe plate are two vertical, spaced apart plates or flanges 22 and two similar plates or flanges 24 depend in spaced apart vertical relation from the heel plate, the plates 22 and 24 constituting 100 hangers for front and rear truck brackets 26, of standard construction, to which are pivoted, in the usual manner, trucks 105 carrying axles 27 upon which the rollers 28 are mounted. 110

To prevent flatwise bending or buckling of the footplate under the strains to which it is subjected in use, the present invention provides for reinforcing or bracing the same 5 in an improved and novel manner. To this end a pair of stiffening ribs or plates 32 are rigidly secured to the lower side of the toe plate 6. The stiffening ribs are preferably formed as continuations of the front hanger 10 plates 22 as shown and extend therewith lengthwise of the toe plate from substantially its middle portion to the rear extremity of its extension 8. As shown, the stiffening ribs 32 are disposed in parallel 15 planes perpendicular to the toe plate and adjacent the lateral edges of the extension 8. Thus the ribs 32, together with the portions of the toe plate disposed between said ribs, form a structure substantially U-shaped 20 in cross section, this structure constituting, in effect, an inverted U-beam or girder. A second pair of parallel stiffening ribs or plates 34 are arranged beneath the heel plate 5 and have their upper edges rigidly secured 25 thereto. These ribs are also preferably formed as continuations of the rear hanger plates 24 and extend therewith lengthwise of said plate from its rear edge to the forward end of its extension 7 and being located adjacent the lateral edges of said extension. 30 This second pair of stiffening ribs 34 serves, in conjunction with the intervening portion of the heel plate to constitute, in effect, a second inverted U-beam structure or girder 35 member. The above-described girder members are constructed and arranged to inter-slide in telescopic relation, i. e., with their upper walls and their respective side walls in sliding contact. Thus it will be seen that 40 the two pairs of stiffening ribs 32 and 34 by virtue of their overlapping relation serve to prevent relative lateral or edgewise displacement of the toe and heel plates, as well as to impart the required rigidity to said plates. 45 When the toe and heel have been secured together by the fastening means 9, the described girder members are rigidly connected and act as a single truss member to brace the foot plate against vertical pressure. 50 To positively prevent vertical or relative flatwise displacement of the toe and heel plates, the stiffening ribs 32 are set inwardly a slight distance from the lateral edges of the toe plate extensions 8 to provide narrow 55 flanges 23 which project outwardly beyond said ribs while the heel plate stiffening ribs 34 are shaped transversely to form, in conjunction with the heel plate, channels 29 to receive the flanges 23. To obtain the requisite cross-sectional shape of the stiffening ribs 34, each of said ribs is bent transversely 60 to provide vertically offset upper and lower portions adjacent the longitudinal edges of the rib and an intermediate portion 25 perpendicular to said offset portions. The

upper and lower offset portions of the ribs 34 are disposed at right angles to the heel plate and are adapted for sliding engagement with the opposite longitudinal edges of the toe plate extension 8 and the outer faces 70 of the toe plate stiffening ribs 32, respectively. The intermediate portions 25 extend parallel to the heel plate and are adapted for sliding engagement with lower faces 75 of the flanges 23 of the latter. This construction is such as positively to prevent relative vertical flatwise as well as lateral edgewise displacement of the toe and heel plates. Thus it will be seen that the fastening device 80 9 is not relied upon to hold the toe and heel plate extensions against relative flatwise displacement inasmuch as this result is effectively accomplished by the interfitting of the toe plate flanges 23 with the channels 29 formed beneath the heel plate. 85

The invention has been disclosed herein in an embodiment at present preferred for illustrative purposes, but the scope of the invention is defined by the appended claims rather than by the foregoing description. 90

Claims:

1. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a girder member extending rearwardly from the toe plate and a girder member extending forwardly from the heel plate, said girder members having vertical portions in intersliding engagement, one of said girder members having horizontal tongue portions and the other of said girder members having horizontally disposed groove portions for receiving said tongue portions for intersliding fit therewith. 100

2. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a girder member extending rearwardly from the toe plate and a girder member extending forwardly from the heel plate, said girder members having vertical portions in intersliding engagement, one of said girder members having horizontal tongue portions coextensive therewith and the other of said girder members having horizontally disposed groove portions coextensive therewith for receiving said tongue portions for intersliding fit therewith. 110

115

120

125

130

3. In a roller skate, a toe plate having a front hanger depending therefrom, a heel plate having a rear hanger depending therefrom, front and rear skate rolls mounted in 5 said front and rear hangers respectively, means for interconnecting said toe plate and heel plate for adjusting the lengthwise relation between the same and between said front and said rear skate rolls comprising 10 a girder member extending rearwardly from the toe plate and a second girder member extending forwardly from the heel plate, said girder members being substantially U-shaped in cross section and having their 15 open sides facing downwardly, horizontal tongue portions on one of said girder members and horizontal groove portions on the other of said girder members for receiving said tongue portions for intersliding fit therewith, a hanger on said toe plate having vertical side flanges formed as extensions of the opposed sides of the first girder member, and a hanger on said heel plate having vertical side flanges formed as 20 extensions of the opposite sides of the second girder member.

4. In a roller skate, a toe plate having a front hanger depending therefrom, a heel plate having a rear hanger depending therefrom, front and rear skate rolls mounted in 30 said front and rear hangers respectively, means for interconnecting said toe plate and heel plate for adjusting the lengthwise relation between the same and between said 35 front and said rear skate rolls comprising a girder member extending rearwardly from the toe plate and a second girder member extending forwardly from the heel plate, said girder members being substantially U-shaped in cross-section and having their 40 open sides facing downwardly, horizontal tongue portions on the first girder member and horizontal groove portions on the second girder member and coextensive therewith for receiving said tongue portions for intersliding fit therewith, a hanger on said toe plate having vertical side flanges formed as 45 extensions of the opposed sides of the first girder member, and a hanger on said heel plate having vertical side flanges formed as 50 extensions of the opposite sides of the second girder member.

5. In a roller skate, a toe plate having a front hanger depending therefrom, a heel plate having a rear hanger depending therefrom, front and rear skate rolls mounted in 55 said front and rear hangers respectively, means for interconnecting said toe plate and heel plate for adjusting the lengthwise relation between the same and between said front and said rear skate rolls comprising a girder member extending forwardly from 60 said heel plate and substantially U-shaped in cross section with its open side facing downwardly, a second girder member ex-

tending rearwardly from said toe plate and substantially U-shaped in cross-section with its open side facing downwardly, said girder members having an intersliding fit one upon the other so that their vertical portions prevent lateral displacement thereof, horizontal groove portions on one girder member and horizontal tongue portions upon the other girder member adapted to slide in fitted relation with said groove portions to prevent vertical displacement of said girder members. 70

6. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a girder member extending forwardly from 80 said heel plate and substantially U-shaped in cross-section with its open side facing downwardly, a second girder member extending rearwardly from said toe plate and substantially U-shaped in cross section with its open side facing downwardly, said girder members having an intersliding fit one upon the other so that their vertical portions prevent lateral displacement thereof, horizontal groove portions on one girder member and horizontal tongue portions upon the other girder member adapted to slide in fitted relation with said groove portions to prevent vertical displacement of said girder members. 85

7. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a girder member extending forwardly from 90 said heel plate and substantially U-shaped in cross-section with its open side facing downwardly, a second girder member extending rearwardly from said toe plate and substantially U-shaped in cross section with its open side facing downwardly, said girder members having an intersliding fit one upon the other so that their vertical portions prevent lateral displacement thereof, horizontal groove portions on one girder member and horizontal tongue portions upon the other girder member adapted to slide in fitted relation with said groove portions to prevent vertical displacement of said girder members. 95

7. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a girder member extending forwardly from 100 said heel plate and substantially U-shaped in cross-section with its open side facing downwardly, a second girder member extending rearwardly from said toe plate and substantially U-shaped in cross section with its open side facing downwardly, said girder members having an intersliding fit one upon the other so that their vertical portions prevent lateral displacement thereof, and one of said girder members having a longitudinal slot in its upper side, horizontal groove portions on one girder member, horizontal tongue portions on the other girder member adapted to slide in fitted relation with said groove portions to prevent vertical displacement of said girder members, a clamping bolt extending through said slot and 105

- through the upper side of the unslotted girder member, and a nut on said bolt located within the opposed side of the inner girder member.
5. In a roller skate, a toe plate having a front hanger depending therefrom, a heel plate having a rear hanger depending therefrom, front and rear skate rolls mounted in said front and rear hangers respectively,
10. means for interconnecting said toe plate and heel plate for adjusting the lengthwise relation between the same and between said front and said rear skate rolls comprising a girder member extending forwardly from
15. said heel plate and substantially U-shaped in cross section with its open side facing downwardly, a second girder member extending rearwardly from said toe plate and substantially U-shaped in cross-section with
20. its open side facing downwardly, said second girder member having a longitudinal slot in its upper side and having a sliding fit within the first girder member so that the vertical portions of said girder members prevent
25. lateral displacement thereof, horizontal groove portions on one girder member, horizontal tongue portions on the other girder member adapted to slide in fitted telescopic relation with said groove portions to prevent vertical displacement of said girder members, and means for clamping said girder members together in various positions of longitudinal adjustment whereby
30. said heel plate and its respective hanger and rear skate roll may be adjustable lengthwise with respect to said toe plate, its respective hanger and front skate roll.
9. In a roller skate, an extensible foot plate comprising a heel plate and a toe plate adjustable longitudinally with respect to each other, said heel plate having a rear hanger fixed thereto and said toe plate having a front hanger fixed thereto, front and rear skate rolls mounted in said front and rear hangers respectively, a pair of vertically arranged stiffening ribs rigidly attached to each of said plates, each pair of the said ribs together with the portion of the foot plate to which it is attached being extended to form a longitudinally arranged inverted U-beam, said beams being adapted to slide telescopically one within the other, flanges on one of said U-beams formed by the projection of its upper wall beyond its side walls, and channels extending throughout the length of the other U-beam to receive said flanges to prevent lateral edgewise displacement of said beams.
10. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a forward extension from said heel plate and rearward extension from said toe plate, a pair of stiffening ribs depending from the said heel plate, said ribs having inwardly bent portions adjacent their upper longitudinal portions cooperating with the latter and with said plate to provide channels for receiving the longitudinal edges of the extension of the toe plate thereby permitting relative longitudinal adjustment of said plates and preventing relative flatwise displacement thereof and means on the toe plate cooperating with the lower longitudinal portions of said ribs for preventing lateral edgewise displacement of said plates.
11. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a forward extension from said heel plate and rearward extension from said toe plate, a pair of stiffening ribs depending from one of said plates, said ribs having inwardly bent portions adjacent their upper longitudinal portions cooperating with the latter and with said plate to provide channels for receiving the longitudinal edges of the extension of the other plate, thereby permitting relative longitudinal adjustment of said plates and preventing relative flatwise and lateral edgewise displacement thereof, and a second pair of stiffening ribs depending from the other plate and adapted to slide between the first mentioned ribs.
12. In a roller skate, a toe plate having a front hanger depending therefrom, a heel plate having a rear hanger depending therefrom, front and rear skate rolls mounted in said front and rear hangers respectively, means for interconnecting said toe plate and heel plate for adjusting the lengthwise relation between the same and between said front and said rear skate rolls comprising a forward extension from said heel plate and rearward extension from said toe plate, a pair of stiffening ribs depending from said heel plate, said ribs having inwardly bent portions adjacent their upper longitudinal portions cooperating with the latter and with said plate to provide channels for receiving the longitudinal edges of the extension of the toe plate thereby permitting relative longitudinal adjustment of said plates and preventing relative flatwise and lateral edgewise displacement thereof, and a second pair of stiffening ribs depending from the toe plate and adapted to slide between the first mentioned ribs.

13. In a roller skate, a heel plate, a hanger comprising vertical side plates depending from the heel plate, a rear skate roll mounted in said hanger, a girder member extending forwardly from the heel plate and substantially U-shaped in cross section with its open side facing downwardly, said member being formed by extending said heel plate and the vertical side plates of said hanger, 45
- 5 a toe plate, a hanger comprising vertical side plates depending from the toe plate, a front skate roll mounted in said hanger, a second girder member extending rearwardly from the toe plate and substantially 50
- 10 U-shaped in cross section with its open side facing downwardly, said second girder member being formed by extending said toe plate and the vertical side plates of said hanger, said girder members having 55
- 15 an intersliding fit one upon the other so that their vertical portions prevent lateral displacement thereof, horizontal groove portions on one girder member and horizontal tongue portions on the other girder member 60
- 20 adapted to slide in fitted relation with said groove portions to prevent vertical displacement of said girder members. 65
14. In a roller skate, a toe plate having a front hanger depending therefrom, a heel 70
- 30 plate having a rear hanger depending therefrom, front and rear skate rolls mounted in said front and rear hangers respectively, means for interconnecting said toe plate and heel plate for adjusting the lengthwise 75
- 35 relation between the same and between said front and said rear skate rolls comprising a girder member extending forwardly from said heel plate and substantially U-shaped in cross section with its open side facing 80
- 40 downwardly, a second girder member extending rearwardly from said toe plate and substantially U-shaped in cross-section with its open side facing downwardly, said girder members having an intersliding engagement to prevent vertical displacement of said girder members. 85

In testimony whereof I have affixed my signature.

ARTHUR L. STAPLES.
